Attorney

UNITED STATES PATENT OFFICE.

WILLIAM WESTENFIELD, OF CORONA, SOUTH DAKOTA.

SMOKING-PIPE.

1,245,078.

Specification of Letters Patent.

Patented Oct. 30, 1917.

Application filed October 11, 1916. Serial No. 125,039.

To all whom it may concern:

Be it known that I, WILLIAM WESTENFIELD, a citizen of the United States, residing at Corona, in the county of Roberts and

5 State of South Dakota, have invented certain useful Improvements in Smoking Pipes, of which the following is a specification, reference being had therein to the accompanying drawing.

10 The invention relates to smoking pipes, and has for its primary object to provide a pipe of this character wherein the bowl thereof for containing the tobacco is of novel form so as to avoid the wasting of 15 the tobacco or the falling of the same therefrom when the pipe is used or at rest upon a support.

Another object of the invention is the provision of a pipe wherein the construction 20 thereof will avoid the blowing of ashes into the face of the user thereof when subjected to strong winds and also the fire in the burning of the tobacco will be retained to avoid the flying of sparks in the smoking 25 of the pipe.

A further object of the invention is the provision of a pipe of this character wherein the bowl construction thereof will permit the reception of a maximum quantity of 30 tobacco and in the smoking of the pipe the nicotin will be trapped therein so as to avoid the choking of the stem or mouthpiece of the pipe and the swallowing of the nicotin while in the act of smoking the pipe.

35 A still further object of the invention is the provision of a pipe of this character which is simple in construction, thoroughly sanitary and clean at all times, reliable and efficient in its purpose, strong, durable and 40 inexpensive in manufacture.

Other objects will be in part obvious and in part hereinafter set forth.

The invention accordingly consists in the features of construction, combination of elements and arrangement of parts which will 45 be exemplified in construction hereinafter described, and the scope of the application of which will be indicated in the appended claim.

50 In the drawings:

Figure 1 is a perspective view of a pipe constructed in accordance with the invention;

55 Fig. 2 is an end view showing the cap or closure member open;

Fig. 3 is an enlarged vertical longitudinal sectional view through the pipe; and Fig. 4 is a sectional view of Fig. 3.

Similar reference characters indicate corresponding parts throughout the several views of the drawing.

Referring to the drawing in detail, A designates generally the bowl, B the stem and C the mouthpiece of the smoking pipe hereinafter fully described in detail.

The bowl A is formed with a tobacco charging chamber 5 which opens through the front or forward end of said bowl, while the top of the bowl is provided with an air intake port or opening 6 communicating with the chamber 5, the chamber 5 being filled with tobacco through the open end thereof, and said tobacco is lighted through the port or opening 6. This bowl at its bottom is provided with a rest 7 so that the pipe, when not in use, can be placed upon a support for the standing of the same thereon without possibility of the toppling over or upsetting of the pipe when at rest.

The open end of the chamber 5 in the bowl 6 is closed through the medium of a cap or closure member 8 which is of a shape corresponding to the cross sectional shape of the bowl A and is swingingly supported upon a pivot 9 which is securely mounted in the bowl. On the said bowl A is formed a stop 10, against which abuts the cap or closure member 8 when closed so that the latter is restricted in its closing movement, the stop 10 being located at a lower point on the bowl so that on closing movement of the cap or closure member 8 it will rest upon the stop and there will be no possibility of the accidental opening movement thereof so that the tobacco will be retained in the chamber 5 without the possibility of waste or the falling of the tobacco therefrom when the pipe is being smoked or at rest.

The stem B is formed with a well or reservoir 11 through the inner closed end of which communicates a passage 12 which leads from the inner closed end of the chamber 5 within the bowl A, and into this passage is introduced a draft tube 13 which is readily removable from said passage for cleaning purposes, and in the smoking of the pipe draft is had through the tube 13 which protrudes through the well or reservoir 11, into the outer end of which is fitted a removable mouth-

piece 14, the same being formed with an outwardly tapered bore or passage 15 which opens through opposite ends of the mouth-piece and is located centrally thereof, the 5 tube 13 being also protruded into the bore or passage 13 so that the smoke will travel into the mouth of the user of the pipe through the mouthpiece 14, as usual, and on the drawing of nicotin from the chamber 5 the same 10 flows from the tube 13 and drops into the well or reservoir 11 for the collection thereof at this point. Upon the removal of the mouth-piece 14 the nicotin and other matter collected within the well or reservoir 11 can be 15 extracted therefrom for the thorough cleaning of the pipe. Also, the tube 13 can be removed for the cleaning thereof should the same become choked or unsanitary.

It is of course to be understood that the 20 invention is not restricted to the use of materials, shape of the component parts, the size of the chamber 5 and well 11, nor the length of the tube 13 or any other detail proportions, parts and minor arrangements, 25 as changes, variations, modifications may be made such as come properly within the scope of the appended claims without departing from the spirit of the invention or sacrificing any of its advantages.

30 From the foregoing description, taken in connection with the accompanying drawing,

the construction and operation of the herein described pipe will be readily apparent and, therefore, a more extended explanation has been omitted.

35

Having thus described my invention, I claim:

A pipe consisting of a bowl having its outer end open and formed upon its top with an opening, an integral stop formed flush 40 with one of the lower corners of the bowl upon the edge of the open end thereof, said stop having a diagonally inclined edge disposed at one side of the center of the bowl, a single pivot pin mounted upon the outer 45 edge of said bowl centrally but at the upper end thereof, and a lid fulcrumed upon said pivot at its outer end eccentrically of said bowl and provided with an inclined bottom edge extending from an intermediate point 50 of the width of said lid and terminating laterally thereof near a point centrally of the top and bottom thereof so that when the inclined edge of said lid engages the inclined edge of said stop it will be in closed position 55 and have its greater weight acting from the side opposite said stop to cause said inclined edges of the lid and stop to frictionally engage.

In testimony whereof I affix my signature. 60

WILLIAM WESTENFIELD.
